LEON WYGODSKY, OF BALTIMORE, MARYLAND, ASSIGNOR TO BALTIMORE OIL ENGINE COMPANY, OF BALTIMORE, MARYLAND, A CORPORATION OF DELAWARE.

INTERNAL-COMBUSTION ENGINE.

1,383,367.

Specification of Letters Patent.

Patented July 5, 1921.

Application filed August 22, 1917. Serial No. 187,662.

To all whom it may concern:

Be it known that I, LEON WYGODSKY, a citizen of the United States of America, and resident of Baltimore, Maryland, have invented certain new and useful Improvements in Internal-Combustion Engines, of which the following is a specification.

My invention relates to improvements in internal combustion engines, particularly engines using heavy oil as fuel, and still more particularly, engines in which air for combustion is compressed in the engine cylinders, and then, at a suitable period in the cycle, fuel oil is injected in the form of spray. The engine herein described is of the two-cycle type, though in many respects it is not necessarily limited to the two-cycle type; and is composed of a multiple of cylinder structures, each such structure comprising two pistons working in opposite directions relatively, and on opposite sides of a single compression space within that cylinder structure. In practice, each unit of the engine (there may be one or more units) comprises two such cylinder structures. In general, there will be two crank shafts for each unit of the engine, together with suitable means for transferring power from the one crank shaft to the other; and, in general, the cylinders will be arranged approximately vertically, though, usually, at some angle to the vertical, air being admitted to the compression space through ports controlled by one piston, and the exhaust gases being discharged through ports uncovered by the other piston. Such air is supplied by so-called scavenging pumps operated, preferably, by the mechanism which transmits power from the one crank shaft to the other. These scavenging pumps also serve as an air motor for starting and reversing the engine.

My invention consists in the novel arrangement of cylinders, in the novel mechanism for transmitting power from the one crank shaft to the other, in the novel arrangement of the scavenging pumps mentioned with respect to such power transmitting mechanism, and in various other features hereinafter described and particularly pointed out in the appended claims.

The objects of my invention are to improve internal combustion engines, particularly engines of the fuel-injection type, and

still more particularly engines of the multi-cylinder, self-starting and reversing type; to insure high economy of operation; to render the engine compact and simple, extremely light and easy of construction; to so design the engine that the various parts thereof shall be relatively small and relatively accessible; to provide for the thorough scavenging of the engine cylinders, objects of my invention will appear hereafter.

I will now proceed to describe my invention with reference to the accompanying drawings, and will then point out the novel features in claims.

Figure 1 shows an end elevation of one form of engine embodying my present invention; Fig. 2 shows a transverse vertical section of the engine, through the center of one of the cylinder structures; Fig. 3 shows a partial side view and partial oblique section on the line 3-3 of Fig. 2; Fig. 4 shows an end elevation and partial central vertical section of the mechanism for transmitting motion from the upper to the lower crank shaft and of two of the scavenging pump cylinders, one of which cylinders is shown in central vertical section on the line 5-5 of Fig. 5; Fig. 5 shows a horizontal section of the scavenging pump on the irregular section line 6-6 of Fig. 4; Fig. 6 shows a perspective elevation of several connected frames of the power units of the engine; Fig. 7 is a detail axial vertical section through one of the intermediate cylinder structures, and its corresponding guide cylinders, the guide cylinders having been removed somewhat from the intermediate cylinder structure to make clear the form of the ports; in this view the pistons are also shown, the upper piston being partly broken away; Fig. 8 shows a side elevation of one of the pistons, the view being on a larger scale than the previous views; Fig. 9 shows an end view of one of the guide cylinders.

In the drawings 1 designates the engine frame, described more particularly hereinafter; 2 designates a combustion-chamber and working-cylinder structure, to which are attached guide cylinders 3. 4 designates the engine pistons, 5 designates a lower crank shaft, and 5^a an upper crank shaft, power being transmitted from the one crank shaft to the other by mechanism hereinafter de-

scribed. 6, 6 designate jacketed air-inlet manifolds, to which air is supplied by the scavenging pumps as hereinafter described, and from which air passes, at suitable times, 5 to a belt of inlet ports 7, for each cylinder structure 2, uncovered by the upper piston 4 of that structure when that piston nears the outboard or upper end of its stroke. 8 designates a jacketed exhaust manifold, to which 10 exhaust gases pass from a port belt 9, for each cylinder structure 2, which port belt is uncovered by the lower piston 4 of that structure when such piston nears the lower or outboard end of its stroke. 10 and 11 are 15 the cylinders proper, located within the cylinder structure 2, with their axes angularly related relatively. This engine is designed to work at a moderately high compression pressure, and, therefore, a small clearance 20 space is necessary when the two pistons 4 are at the inboard limits of their stroke. The piston heads are provided with curved surfaces 14 and 15, between which surfaces, when the two pistons are at the inboard ends 25 of the stroke, there will be a clearance space, in which air, compressed by the rearward motion of the pistons, will lie, and into which oil may be sprayed by a suitable sprayer set into the port 17.

30 In order to reduce the clearance space to obtain the desired compression pressure, part of each piston is cut away, so as to provide plane oblique surfaces, 12, 13, as clearly shown in Fig. 8, where the surface 12 is 35 shown.

The operative portions of cylinders 10 are larger than the operative portions of cylinders 11, thus permitting the pistons on exhaust end to open the exhaust prior to the 40 pistons on the admission end opening the admission.

The port belts 7 and 9 are formed, in the guide cylinders 3, as slots separated by port-bridges, which slots are open at the inboard 45 ends of the guide cylinders 3, so far as those cylinders are concerned, but are closed by the proximate surfaces of the cylinder structure 2. These guide cylinders 3 are bolted to the cylinder structure 2. The general 50 structure is such as to provide a clear flow for air into, and clear flow for exhaust gases out of, the cylinders, when the ports are uncovered by the corresponding pistons. Owing 55 to the fact that the exhaust is from the ports at the bottom of the cylinder structure 2, any liquid or solid deposits in the cylinder structure will be swept out of the exhaust ports by the exhaust gases and by air entering the admission ports. The 60 pistons are connected to the cranks of the crank shafts 5 and 5^a by the usual connecting rods 18 and 19. As shown particularly in Fig. 3, one of the connecting rods working on each 65 crank pin is forked, the connecting rod of the laterally opposite cylinder working on

that same crank pin, and having its end lying within the fork of the other connecting rod working on that crank pin. Assuming, for the moment, the air is supplied under pressure from scavenging pumps, to be mentioned hereinafter, to the inlet manifolds 6, and assuming, for the present, the transmission of power by means hereinafter described, from the one crank shaft to the other, the operation of the engine is as follows:

In Fig. 2, the pistons 4 of the left hand side of the engine are shown in such position that the air inlet ports and the exhaust ports are open. Air for scavenging purposes, and for the supporting of combustion during the next ensuing power stroke, is, therefore, passing from manifold 6 through the air admission ports 7, and is also sweeping exhaust gases of the previous power stroke out 85 through the exhaust ports 9 and exhaust manifold 8. Immediately after the beginning of the inboard strokes of the pistons 4, the ports 7 and 9 are closed by said pistons, and each pair of coacting pistons then compresses the air within the cylinder structure, until, finally, the pistons reach the extreme inboard position indicated in dotted lines in Fig. 2. At or about this time oil is injected through the sprayers into the compression 95 space between the pistons, ignition taking place either due to the high temperature of the walls of this space, or by reason of the oil spray being ignited by igniters 20. The pistons then move apart, under the influence 100 of the pressure due to the ignition of the charge, and when, near the outboard ends of the strokes of the pistons, ports 7 and 9 are uncovered, exhaust and air admission occur, the air sweeping the exhaust products out of 105 the cylinder structure, as previously described. The lateral thrusts produced by these pistons are taken by the corresponding diagonal tie rods hereinafter mentioned. Owing to the large number of cylinders in 110 each unit of the engine, the thrust produced by any one cylinder and its corresponding piston in any direction is relatively small; a condition which facilitates operation at high rotative speed. The two crank shafts revolve in opposite directions, power being 115 transmitted from the one to the other by means hereinafter described.

To take down a guide cylinder, or to remove an engine piston, is an exceedingly 120 simple matter. The central cylinder-structure 2 is attached directly to the engine frame. The two guide cylinders 3 are supported by this central cylinder structure 2. The joints between successive sections of the inlet manifolds 6 and exhaust manifolds 8 are plain-faced joints, as hereinafter described. To remove one of the guide cylinders 3, therefore, all that is necessary is to introduce a bolt (not shown) into holes 21 130

and 22 of the guide cylinder and piston, when those holes have been brought into registry, so locking the guide cylinder and piston together; remove the bolts, connecting 5 such guide cylinder to the central cylinder structure 2; and then swing that guide cylinder down, or up, as the case may be. With the guide cylinder so swung down, or up, and away from the cylinder structure 2, the 10 removal of the piston within that guide cylinder is, obviously, a very simple matter.

Obviously, means must be provided for the transmission of motion from shaft 5^a to shaft 5 or vice versa, that the shafts may 15 rotate in synchronism; and, obviously, such transmission means must be capable of transmitting considerable power. Without limiting myself to any particular means for this purpose, I have illustrated, particularly in 20 Figs. 3, 4, and 5, a very suitable mechanism. The crank shafts 5 and 5^a are provided with corresponding crank pins 23 and 24, located 90 degrees apart, in the construction shown, and on these crank pins are mounted bearing blocks 25, arranged to slide horizontally and 25 transversely on bearing surfaces formed on I-shaped members 26, themselves mounted to reciprocate vertically between stationary guides 27 provided on the engine frame. 30 These members 26 are hollow, and, so far as may be, of circular cross-section, and within their upper and lower horizontal arms are guide-sleeves 28, connected to the sliding bearing-blocks 25 by bolts 29 themselves 35 working in suitable slots in members 26. By means of these sleeves 28 and bolts 29, the bearing-blocks 25 are held to their respective guide-surfaces of the members 26.

In a general way, the structure comprising 40 the vertically-sliding I-shaped members 26 upon which the crank-pin bearing blocks 25 slide, forms the equivalent of parallel rods connecting the two crank shafts 5 and 5^a; with this exception, however, that in the construction shown the direction of rotation of 45 the two crank shafts need not be the same, but may be opposite; and as a matter of fact, in the structure shown the parts are arranged for rotation of the two crank shafts 5 and 5^a in opposite directions.

It is desirable that the engine be provided with air-compressing means, for the supply of scavenging air to the cylinders; and it is also convenient to use the air pumps as air 55 motors in starting and reversing the engine. Compactness and efficiency are promoted by operating the air pumps by means of the I-shaped members 26; the upper and lower horizontal arms of said members being connected by piston rods 30, carrying pistons 31 working in stationary cylinders 32 secured to convenient portions of the engine frame. Each of these pump cylinders 32 is "double-acting," having upper and lower admission 60 valves, whereby, during each suction stroke,

air is admitted to the appropriate side of the pump cylinder; and having also upper and lower discharge valves 34, whereby, at a suitable point in each compression stroke, the air compressed is released into a receiver 70 space 35, whence the compressed air is conducted, by a pipe 36, forming a continuation of the receiver space, to the air inlet manifolds 6. There being four double-acting 75 pump cylinders, each of large capacity, operating at the speed of the main engine, the supply of air for scavenging and for cylinder-charging is ample the claims covering the above transmission mechanism and scavenging pump form the basis for other applications. 80

As indicated in the lower part of Fig. 5, the receiver space of each inner valve chamber communicates with the receiver space of the corresponding outer valve chamber, and 85 so to the air inlet manifold.

The engine is provided with a suitable fuel supply pump supplying fuel at high pressure to the sprayers. The engine will also be provided with some means for compressing 90 air to high pressure for starting purposes, or an auxiliary air pump may be provided for that purpose; but these are usual auxiliaries of engines of this type, and I have not thought it necessary to illustrate such auxiliaries herein. As previously mentioned, the scavenging pumps are used as an air motor for starting and reversing the main engines. 95

Relief valves 47 are provided on the heads 100 of the pump cylinders to prevent production of excessive pressures.

It will be noted, with respect to Figs. 1 and 2 particularly, that each admission manifold 6 and each exhaust manifold 8, is integral with corresponding guide cylinder 4, and that the water jackets of these manifolds are in one with the water jackets of the guide cylinders. The central cylinder-structures 2 have separate jackets, connected as 110 shown to the jackets of the inlet and exhaust manifolds. Suitable packing, of course, is placed in the joints between adjacent sections of the manifolds 6 and 8.

What I claim is: 115

1. An internal combustion two-cycle engine, comprising two crank shafts, a cylinder structure comprising two pistons working in the same cylinder structure and connected one to one crank shaft, and the other to the other crank shaft, said pistons arranged to approach each other within the cylinder structure closely, at the inboard limits of their strokes, the cylinder structure comprising inlet and outlet ports arranged to be 120 uncovered, the one by the one piston, and the other by the other piston, and comprising also means for introducing air within said cylinder structure between said pistons and means of introducing fuel at a determined 125 130 135

point of stroke between said pistons, and means for insuring synchronous rotation of said two crank shafts.

2. An internal combustion two-cycle engine, comprising two crank shafts, a cylinder structure, two pistons working in the same cylinder structure and connected one to one crank shaft, and the other to the other crank shaft, said pistons having a portion of the heads of each provided with mutually parallel faces and arranged to approach each other within the cylinder structure closely, at the inboard limits of their strokes, the cylinder structure comprising inlet and outlet ports arranged to be uncovered, the one by the one piston, and the other by the other piston, and comprising also means for introducing air and fuel into the space between said pistons, and means for insuring synchronous rotation of said crank shafts, the direction of movement of said pistons being at an angle one to the other.

3. An internal combustion two-cycle engine comprising two crank shafts, one above the other, a cylinder structure, two pistons working in the same cylinder structure and connected one to one crank shaft, and the other to the other crank shaft, said pistons having a portion of the heads of each provided with mutually parallel faces and arranged to approach each other within the cylinder structure closely, at the inboard limits of their strokes, the cylinder structure comprising inlet and outlet ports arranged to be uncovered, the one by the one piston, and the other by the other piston, and comprising also means for introducing air and fuel into the space between said pistons, and means for insuring synchronous rotation of said crank shafts, the direction of movement of said pistons being at an angle one to the other.

4. An internal combustion two-cycle engine comprising two crank shafts, two cylinder structures, two pistons working in the same cylinder structure and connected one to one crank shaft and the other to the other crank shaft by connecting rods, the axes of all four of said connecting rods swinging in substantially the same plane, each such two pistons arranged to approach each other within their respective cylinder structure closely, at the inboard limits of their strokes, each such cylinder structure comprising inlet and outlet ports arranged to be uncovered, the one by one piston, and the other by the other piston, and comprising also means for introducing air and fuel into the space between said pistons, and means for insuring synchronous rotation of said two crank shafts in opposite directions respectively.

5. An internal combustion two-cycle engine comprising two crank shafts, two cylinder structures, two pistons working in the same cylinder structure and connected one to

one crank shaft and the other to the other crank shaft, each such two pistons having a portion of the heads of each provided with mutually parallel faces and arranged to approach each other within their respective cylinder structures closely, at the inboard limits of their strokes, each such cylinder structure comprising inlet and outlet ports arranged to be uncovered, the one by the one piston, and the other by the other piston, and comprising also means for introducing air and fuel into the space between said pistons, and means for insuring synchronous rotation of said two crank shafts in opposite directions respectively, the direction of movement of said pistons being at an angle one to the other.

6. An internal combustion two-cycle engine comprising two crank shafts, one above the other, two cylinder structures, two pistons working in the same cylinder structure of each and connected one to one crank shaft and the other to the other crank shaft, each such two pistons arranged to approach each other within their respective cylinder structures closely, at the inboard limits of their strokes, each such cylinder structure comprising inlet and outlet ports arranged to be uncovered, the one by the one piston, and the other by the other piston, and comprising also means for introducing air within said cylinder structures between said pistons and means of introducing fuel at a determined point of stroke between said pistons and means for insuring synchronous rotation of said two crank shafts in opposite directions respectively.

7. An internal combustion two-cycle engine, comprising two crank shafts, a cylinder structure, two pistons working in the same cylinder structure and connected one to one crank shaft, and the other to the other crank shaft, said pistons arranged to approach each other within the cylinder structure closely, at the inboard limits of their strokes, the cylinder structure comprising inlet and outlet ports arranged to be uncovered, the one by the one piston, and the other by the other piston, means for insuring synchronous rotation of said two crank shafts, and air compressing means driven by said means for insuring synchronous rotation, and arranged to supply air to said inlet ports.

8. An internal combustion two-cycle engine, comprising two crank shafts, a cylinder structure, two pistons working in the same cylinder structure and connected the one to one crank shaft, and the other to the other crank shaft, said pistons arranged to approach each other within the cylinder structure closely, at the inboard limits of their strokes, the cylinder structure comprising inlet and outlet ports arranged to be uncovered, the one by the one piston, and the other by the other piston, means for insur-

ing synchronous rotation in opposite directions respectively of said two crank shafts, and air compressing means driven by said means for insuring synchronous rotation, 5 and arranged to supply air to said inlet ports.

9. An internal combustion engine comprising an engine frame, upper and lower crank shafts, mounted in bearings in said 10 frame, a working-cylinder structure mounted on said frame between said shafts, and comprising working cylinders that are arranged at an angle one to the other with an intermediate compression space, and guide 15 cylinders with ports in the ends thereof, each mounted as a continuation of one of said working-cylinders, but separable therefrom.

10. An internal combustion engine comprising an engine frame, upper and lower crank shafts, two working-cylinder structures secured to opposite sides of said frame between said shafts, each such working-cylinder structure comprising two working-cylinders arranged at an angle one to the other with an intermediate compression space, and two guide cylinders having ports at the working ends thereof for each such working-cylinder structure, each such guide cylinder arranged adjacent to, and forming a continuation of, one of the working cylinders of the corresponding working-cylinder structure, but separable therefrom.

11. An engine comprising two obliquely 35 related guide cylinders and a central structure containing corresponding working cylinders having a common clearance space and separably attached to said guide cylinder, said guide cylinders comprising each a port belt of which one constitutes inlet ports for both cylinders and the other constitutes exhaust ports for both cylinders.

12. An engine comprising two obliquely 45 related guide cylinders and a central structure containing corresponding working cylinders having a common clearance space, said guide cylinders comprising each a port belt of which one constitutes inlet ports for both cylinders and the other constitutes exhaust ports for both cylinders, the ends of 50 the ports of each such port belt being formed by the ends of the said central structure, which is mechanically separate from but connected to the guide cylinders.

55 13. An internal combustion engine comprising in combination a frame having bearings for two crank shafts, a cylinder structure secured to said frame and comprising two cylinders with a common compression 60 space and guide cylinders forming extensions of said cylinders and secured to said cylinder structure but separable therefrom and provided with port belts and with inlet and exhaust manifolds, said manifolds 65 each adapted for connection to correspond-

ing manifolds of other guide cylinders located therebeside.

14. A piston provided with a conoidal head, a portion of said conoidal head as well as a portion of the adjoining cylindrical part 70 being cut away on a plane parallel to the bisecting plane of the angle between the axes of the operation of two such coöperating pistons.

15. In an internal combustion engine, the 75 combination of upper and lower cylinders with a common compression space therebetween, and pistons in said cylinders arranged to approach and recede relatively, the upper cylinder having an admission port 80 for both cylinders and the lower cylinder an exhaust port for both cylinders, said pistons arranged to open and close one or the other of said ports, respectively, and means for supplying air under pressure to said admission port during the period while said admission and exhaust ports are open, whereby such air sweeps out of the cylinders products of combustion and other material present in said cylinders. 85

16. In an internal combustion engine, the combination of two angularly related cylinders having a common compression space between them, and pistons within said cylinders arranged to approach and recede relatively, said pistons each having mutually parallel surfaces on one side to permit their close approach over a considerable area of 90 piston-head.

17. In an internal combustion engine, the 100 combination of two angularly related cylinders having a common compression space between them, and pistons within said cylinders arranged to approach and recede relatively, said pistons each having oblique surfaces on one side to permit their close approach over a considerable area of piston-head, and having also other oblique surfaces to provide, upon close approach of 105 said pistons, a compression space of shape 110 adapted to receive a wide-spread fuel spray, and means for introducing a fuel spray into such compression space.

18. An engine comprising a cylinder structure proper and a guide cylinder connected to and forming an extension of said cylinder proper, ports being provided in said guide cylinder, which ports extend to that end of the guide cylinder which abuts the cylinder proper, and are closed by the 120 end face of the cylinder proper. 115

19. A cylinder for an internal combustion engine comprising, straight bored ends at an angle with each other and a middle curved section joining said straight bored 125 ends in combination with pistons operating in said straight bored ends conjointly metered at the heads to approach each other with parallel faces.

20. A cylinder for an internal combustion 130

- engine comprising, straight bored ends at an angle with each other and a middle curved section joining said straight bored ends in combination with pistons operating 5 in said straight bored ends conjointly metered at the heads to approach each other with parallel faces and provided with a cut away portion forming in conjunction with said curved middle section a compression 10 and combustion space.
21. A cylinder structure for an internal combustion engine comprising, an elbow having straight bored ends, guide cylinders attached to said straight bored ends and 15 separable therefrom, and means of admission into one of said guide cylinders, and means of exhaust from the other of said guide cylinders, said admission and said exhaust being at the junction of said separable parts.
22. A guide cylinder comprising, a gas passage, a manifold forming a continuation of such gas passage connecting with a similar manifold of a neighboring guide cylinder, ports in said guide cylinder for the conducting of gases and bridges forming such ports, such bridges being open on most of the periphery of the guide cylinder and adjoining the bottom flange of the cylinder 25 proper, thus permitting the exact machining of the point of opening of such ports in combination with a cylinder in an engine.
23. In a multi-cylinder engine, a guide cylinder provided with a manifold for the 30 conducting of gases from ports in said guide cylinder, said manifold alining with the similar manifolds of all the guide cylinders.
24. In an engine, a gas passage leading from circular ports, said passage being of uniform radial dimension with reference to 40 said ports and varying axially with reference to said ports to accommodate volume.
25. In a multi-cylinder engine, a cylinder unit comprising between parallel planes a guide cylinder attached to said cylinder and 45 containing ports in communication with a gas passage terminating at the said parallel planes.
26. A cylinder structure comprising, cylindrical ends in combination with a middle 50 section forming a V figure with unequal legs, thus permitting the shorter leg to cause the opening of the ports of the adjoining guide cylinder sooner as compared with similar ports of the other guide cylinder of the 55 longer leg and also permitting the use of the same guide cylinder for both the exhaust and the air passage, and guide cylinders provided with ports and attached to said cylindrical ends.

60
In testimony whereof I have signed this specification in the presence of two subscribing witnesses.

LEON WYGODSKY.
